UNITED STATES PATENT OFFICE.

CLINTON KLOCK, OF MIDDLEPORT, PENNSYLVANIA.

PERCH STRUCTURE.

1,265,675.

Specification of Letters Patent. Patented May 7, 1918.

Application filed July 3, 1917. Serial No. 178,397.

To all whom it may concern:

Be it known that I, CLINTON KLOCK, a citizen of the United States, residing at Middleport, in the county of Schuylkill and State of Pennsylvania, have invented certain useful Improvements in Perch Structures, of which the following is a specification, reference being had therein to the accompanying drawing.

10 This invention relates to certain new and useful improvements in perch structures and more particularly to that class of perch structures embodying means for holding oil or some other substance to prevent the passage of vermin and it has for its object among others to provide a perch structure wherein the perches are held free from contact with the walls of an inclosure and in which one perch may be moved with respect 15 to another or others to permit cleaning of the oil holding means and free access to the dropping board for cleaning or removing the same.

20 Another object is to provide a hinged section in one or several of the perch brackets embodied in the invention in order that movement and adjustment of the perches may be effected one with respect to the other or others.

25 A further object is to construct one or several of the perch brackets in order that they may be used either in the capacity of vertical supports or wall brackets or both.

With the above and other objects in view, 25 the present invention consists in the combination and arrangement of parts as hereininafter more fully described, illustrated in the accompanying drawings and particularly pointed out in the appended claim, it being 40 understood that changes may be made in the form, proportion, size and minor details without departing from the spirit of the invention.

In the accompanying drawing:

45 Fig. 1 is a side elevation of the perch structure assembled;

Fig. 2 is a fragmentary perspective view of the perch structure;

50 Fig. 3 is a detailed view of the adjustable perch bracket embodied in the invention;

Fig. 4 is a detailed view of the supporting bracket; and

55 Fig. 5 is a slight modification of the brackets used in the invention.

In the drawings wherein is illustrated the preferred embodiment of the invention

like characters of reference indicate like or similar parts.

Secured upon the upper portion of the walls 1 of an inclosure which in this instance is arbitrarily designated as a hen coop by way of illustration, are a pair of adjustable perch supports or brackets generally designated by 2 and each comprising an arm 3 upon which is mounted a freely movable sleeve 4 bent to form foot flanges 5 for attachment to the wall 1; the upper end of the arm being screw threaded to receive a nut 6 to prevent disengagement of the sleeve therefrom. The lower end of 65 the arm 3 is bent as at 7 and is hingedly connected by means of the hinge stud 8 to a screw threaded shank portion 9 driven or screwed into the end of a horizontal perch 10. Disposed intermediate the sleeve 4 and 70 the bent end 7 and concentrically embracing the arm 3 is an oil cup 11 for preventing the passage of vermin from the wall 1 to the perch 10.

A vertical perch 12 has mounted upon the 80 upper ends thereof vertical supports or brackets 13 each having a shaft or body portion 14 provided with screw threaded ends 15 adjacent which are abutment washers 16; one of which abuts the end of the 85 perch 12 and the other abuts the end of the perch 10 which is held in position thereupon by means of the nut 17. Disposed intermediate the abutment washers 16 and concentrically embracing the shaft or body portion 14 is an oil cup 18 for preventing the 90 passage of vermin from the perch 12 to the perch 10.

Attention is called to the fact that the perch 10 may be swung upwardly about 95 the hinged studs 8 of the brackets 2 from engagement with the perch 12 upon removing the nuts 17; thus permitting cleaning of the cups 11 and 18 and also cleaning of the dropping board, (not shown).

As a means for holding the perch 12 securely but in spaced relationship upon the wall 1 slightly modified forms of brackets generally designated by 19 are provided, each of which have substantially S-shaped 105 body portions 20 terminating in feet or securing plates 21 for attachment with the wall 1 and perch 12. Disposed intermediate the feet or plates 21 and concentrically embracing the body portion 20 is an 110 oil cup 22 for preventing the passage of vermin from the wall 1 to the perch 12.

It will thus be seen that the perch structure as an entirety is adequately guarded against the possibility of becoming infested with vermin from adjacent objects, and that 5 each element of the structure is securely mounted in its most advantageous and desirable position.

In addition to the advantages derivative from the peculiar construction of applicant's device as set forth in the above description and illustrated in the accompanying drawings are certain desirable features 10 of simplicity, efficiency and adaptability for the purpose intended that are thought to be 15 evident.

What is claimed is:—

The combination in a perch structure of a horizontal perch, with a vertical support-

ing member for one end thereof, a pair of shanks attached to the other end of the perch, arms hingedly connected to the shanks, means for attaching the arms to a wall that they may stand vertically thereon, members connecting the perch to the vertical support, and oil cups in surrounding relation to said members and the said arms, said oil cups being attached at their bottoms to the arms and to the members but standing in spaced relation thereto for the remainder of their height, whereby vermin are prevented from access to the perch either from the ground or from the wall to which the perch is connected.

In testimony whereof I affix my signature.

CLINTON KLOCK.
